United States Patent Office.

JAMES HUTCHISON, OF NEWARK, NEW JERSEY, ASSIGNOR TO DEBORAH POWERS, ALBERT E. POWERS, AND NATHANIEL B. POWERS, OF LANSINGBURG, NEW YORK.

Design No. 3,990, dated April 26, 1870.

DESIGN FOR A FLOOR OIL-CLOTH PATTERN.

The Schedule referred to in these Letters Patent and making part of the same.

To all whom it may concern :

Be it known that I, JAMES HUTCHISON, of Newark, New Jersey, have invented or produced a new and original Design for Floor Oil-Cloths, or other fabrics, which is fully shown upon the drawings accompanying this specification, which I hereby declare to be a part thereof; and

What is claimed as my invention, and desired to be secured by Letters Patent of the United States, is—
The design for floor oil-cloths, as shown on said drawings, and herein described.

Witnesses: JAMES HUTCHISON.
